United States Patent

Des. 236,898
Patented Sept. 23, 1975

236,898

ELECTRIC MOTOR POWER UNIT OR SIMILAR ARTICLE

Grover P. Holther, Jr., Mount Prospect, Ill., assignor to
Racine Federated Inc.

Filed Mar. 4, 1974, Ser. No. 447,502

Term of patent 14 years

Int. Cl. D13—01

U.S. Cl. D26—5 A

FIG. 1 is a perspective view of the front and a side of the electric motor power unit or similar article showing my new design;

FIG. 2 is a side elevational view on an enlarged scale from the left of FIG. 1;

FIG. 3 is a top plan view on an enlarged scale of FIG. 1;

FIG. 4 is a rear elevational view on an enlarged scale; and

FIG. 5 is a bottom plan view on an enlarged scale.

I claim:

The ornamental design for an electric motor power unit or similar article, as shown and described.
